[57] CLAIM

The ornamental design for a desk pad, as shown.

DESCRIPTION

FIG. 1 is a top, left front perspective view of a desk pad showing my new design;

FIG. 2 is a top plan view;

FIG. 3 is a front elevational view, the rear view being a mirror image thereof;

FIG. 4 is a bottom plan view;

FIG. 5 is a left side elevational view;

FIG. 6 is a right side elevational view thereof; and,

FIG. 7 is a fragmentary, cross-sectional view taken in the direction of arrows 7—7 in FIG. 1.

The FIG. 7 view has been drawn to an enlarged scale with respect to FIGS. 1 through 6.
